UNITED STATES PATENT OFFICE.

CHARLES E. BUELL, OF NEW HAVEN, CONNECTICUT, AND J. FREDERICK BUEL, OF WOBURN, MASSACHUSETTS; SAID CHAS. E. BUELL ASSIGNOR, BY MESNE ASSIGNMENTS, TO THE UNITED STATES TELEPHONE MANUFACTURING COMPANY, OF NEW YORK, N. Y.

ELECTRICAL SIGNALING APPARATUS.

SPECIFICATION forming part of Letters Patent No. 252,288, dated January 10, 1882.

Application filed January 21, 1880.

To all whom it may concern:

Be it known that we, CHARLES E. BUELL, of the city and county of New Haven, State of Connecticut, and J. FREDERICK BUEL, of Woburn, Middlesex county, State of Massachusetts, have jointly invented certain new and useful Improvements in Signaling Apparatus, of which the following is a specification.

Our invention relates to signaling by electricity; and it consists in combining a call-bell magnet and switch with receiving telephone-stations in such a manner that conversation by telephone can neither be overheard nor interrupted.

15 In the accompanying drawings, which form a part of this specification, the same letters and figures refer to corresponding parts in each. Figure 1 is a plan view of the call-bell magnet M, with neutral armature A, having a projection, V, thereon, and arranged in relation to the switch D and pin P, so that when the armature is not attracted the projection V comes between the end of the switch D and pin P and obstructs the moving of the switch D from contact-plate 1 to contact-plate 2. When the armature is attracted the projection V is moved out of the path of the switch D, admitting of its being turned from plate 1 to plate 2, whereby the telephone T is interposed in the main circuit. The circuit is then closed in the direction of the arrows No 1—say from the line-wire to the transmitter F, thence over wire u to the coils of the magnet, thence over wire u' to the switch D, through the switch to the divided contact-plate 2, thence to the telephone T over wire t, and from the telephone over wire t' to contact-plate 1, and off to the line at the right. The moving of the switch D from plate 1 to plate 2 also serves to close the circuit of the local battery B, as indicated by arrows No. 2, from battery B, through wire v, to the primary coil of the transmitter F, thence over wire v' to the switch, over the switch to the divided plate 2, and thence back to the battery over wire v². The local-battery circuit is open when the switch-lever is not in contact with button No. 2. The contact-plate 3 is arranged with a ground-wire, g, and serves the

purpose of a signaling key as the switch D passes in contact therewith to make operative 50 a differential receiving apparatus at a central station to indicate or sound a definite call or signal by varying the tension of the main circuit to a definite degree for each station. The battery B and transmitter F are well-known 55 elements. As the battery charging the main circuit is withdrawn when conversation is being carried on through the telephones, and as the switch D cannot be turned after the battery is removed and the line is in condition for telephonic communication, other stations than those already connected for telephoning cannot interrupt or overhear the communications which are being transmitted, and as each station is arranged to signal its respective call 60 when its switch is turned, no station can interpose its telephone in the main circuit without the fact being known at the central station.

The secondary coil of the transmitter may 70 be included in the telephone branch circuit in the ordinary manner without departing from our invention.

Fig. 2 is a plan view of the magnet M on a movable base, having a hole cut therein, through 75 which the pin P passes. The pin P is disconnected from the base, and is so arranged with relation to the armature A that it will come in contact with the projection V if the base is turned when the armature is not attracted, 80 and prevents the telephone T from being interposed in the main circuit after the battery which charges the main circuit is withdrawn.

Fig. 3 is a side elevation of the switch D as a part of a telephone-holder, and is arranged 85 in relation to the armature A, as shown and described.

Fig. 4 is a plan view of the magnet M and armature A upon a movable base, and arranged in their relation to the pin P so that 90 when the base is turned—while the armature is attracted—the pin P will hold the armature in contact with the screw or point C'; but if the base is turned when the armature is not attracted the pin P serves to hold the armature 95 in contact with the screw or point C². When

the armature is in contact with point C', and the base is turned to plate 2, the telephone is interposed in the main circuit. The moving of the base over the contact-plates *a b c* serves to transmit a signal by making and breaking the circuit. A given number of breaks of the circuit can be made for each station. When the armature A is in contact with the point C² the circuit is permanently closed by the dotted wire F.

Fig. 5 is a side elevation of a cross-section of a call-bell electro-magnet, so constructed and arranged that the bell b covers the entire mechanism of the hammer, armature, and connections except the projecting handle of the switch D. The bell P has a piece rigidly attached to the inside surface thereof for the hammer h to strike against.

Fig. 6 represents a cross-section of a side elevation of a modified form of the call-bell and switch shown in Fig. 5 and described, a single-coil electro-magnet, m, being used, and its core c, which protrudes through the base, being the support for the bell b.

Fig. 7 shows the bell b as covering the electro-magnet, switch, and connections, as shown in figures previously described.

The switch D and contact-pieces 1 2 3 can be detached from the base which supports the call-bell without departing from the invention; and when a press-button key is employed, instead of the switch and contact-pieces shown, for calling a central station, a shield attached to the armature of the electro-magnet can be made to cover the press-button when the armature is in the position termed "open," and thereby prevent interference. (Not shown.) The armatures can be attracted to the sides of the protruding cores of the electro-magnets and neutral or polarized armatures be employed.

We claim—

1. In a telephone-station apparatus, the combination of the following elements, to wit: a main electric circuit, an independent branch circuit including a telephone, and switch devices, substantially such as described, whereby the branch circuit may be interposed in and withdrawn from the main circuit, essentially as herein set forth.

2. The combination, with a charged main telephone-line and a station telephone-circuit, of a switch and an attracted armature of the

electro-magnet included in the said circuit, the switch and the armature being arranged to be interlocked with each other when the attraction of the armature has ceased by the removal of the charging-batteries from the main circuit, substantially as described, whereby the telephone-circuit is prevented from being interposed in the main circuit after the charging-batteries are removed from the main circuit, as set forth.

3. The combination, with a main electric circuit, of a telephone apparatus, substantially as described, provided with a switch and connections arranged to interpose a telephone and transmitter in the said main line, and to simultaneously close a local battery through said transmitter and produce a call or signal upon said main line, as set forth.

4. The combination, in a telephone-station apparatus, of a call-bell electro-magnet included in a main circuit, a telephone, and a transmitter in a branch circuit, with a switch and connections, substantially such as described, whereby the telephone branch circuit may be interposed in the main circuit with the said call-bell electro-magnet, as set forth.

5. The combination, with a charged main electric circuit, including a telephone-station, of a telephone apparatus provided with a switch, an electro-magnet, and an attracted armature, said armature being arranged to lock the switch when the attraction ceases to prevent it being turned to interpose the telephone in the main electric circuit, as set forth, whereby the central office can lock out stations not already interposed by removing the charging-batteries from the main line.

6. The combination, with a single-coil electro-magnet, of a bell attached to and supported by the rod or core which retains the helix of the magnet, substantially as described.

7. The combination, with a call-bell electro-magnet, of a stationary bell arranged to cover the electro-magnet and armature, and having a projecting piece rigidly attached to its inner surface to receive the blows of the armature or hammer, substantially as described.

CHARLES E. BUELL.
